UNITED STATES PATENT OFFICE.

CHARLES E. VERHUNCE, OF WINNETKA, ILLINOIS.

DESIGN FOR A LIGHTING GLOBE.

Application filed May 4, 1923. Serial No. 6,059. Term of patent 3½ years.

To all whom it may concern:

Be it known that I, CHARLES E. VERHUNCE, a citizen of the United States, residing at Winnetka, in the county of Cook and State of Illinois, have invented a new, original, and ornamental Design for Lighting Globe, of which the following is a specification, reference being had to the accompanying drawing, forming a part thereof, in which—

Fig. 1 is an elevation, and
Fig. 2 is a bottom plan view of a lighting globe showing my new design.

I claim:—

The ornamental design for a lighting globe as shown.

CHARLES E. VERHUNCE.
